[57] CLAIM

The ornamental design for a beverage dispenser, substantially as shown and described.

DESCRIPTION

FIG. 1 is a front perspective view of a beverage dispenser, showing my new design;

FIG. 2 is a rear perspective view thereof;

FIG. 3 is a front elevational view thereof;

FIG. 4 is a side elevational view thereof, the other side being a mirror image of the side shown;

FIG. 5 is a rear elevational view thereof; and

FIG. 6 is a top view thereof.

The bottom, not shown, is planar and unornamented.

FIG.1**FIG.2****FIG. 3****FIG. 4****FIG. 5****FIG. 6**
